(57) **CLAIM**

The ornamental design for pear-shaped convertible reading glasses, as shown and described herein.

DESCRIPTION

FIG. 1 is a first perspective view of the pear-shaped convertible reading glasses in a reading glasses configuration.

FIG. 2 is a second perspective view of the pear-shaped convertible reading glasses of FIG. 1.

FIG. 3 is a front view of the pear-shaped convertible reading glasses of FIG. 1.

FIG. 4 is an end view of the pear-shaped convertible reading glasses of FIG. 1.

FIG. 5 is a top view of the pear-shaped convertible reading glasses of FIG. 1.

FIG. 6 is a first perspective view of the pear-shaped convertible reading glasses in a pendant configuration.

FIG. 7 is a second perspective view of the pear-shaped convertible reading glasses of FIG. 6.

FIG. 8 is a front view of the pear-shaped convertible reading glasses of FIG. 6.

FIG. 9 is an end view of the pear-shaped convertible reading glasses of FIG. 6.

FIG. 10 is a top view of the pear-shaped convertible reading glasses of FIG. 6; and,

FIG. 11 is a perspective view of the pear-shaped convertible reading glasses in an intermediate configuration that is between the reading glasses configuration and the pendant configuration.
